M. ABRAMS

Des. 157,717

DRESS

Filed Nov. 10, 1949

FIG. 1.

FIG. 2.

INVENTOR.

MIRIAM ABRAMS

BY

Ed. Abram

ATTORNEY.

UNITED STATES PATENT OFFICE

157,717

DRESS

Miriam Abrams, New York, N. Y., assignor to Barnet Ginsburg & Nat Abelson, Inc., New York, N. Y., a corporation of New York

Application November 10, 1949, Serial No. 5,963

Term of patent 3½ years

(Cl. D3—26)

To all whom it may concern:

Be it known that I, Miriam Abrams, a citizen of the United States, resident of the city of New York, in the county of New York, in the State of New York, have invented a new, original, and ornamental Design for a Dress, of which the following is a specification, reference being had to the accompanying drawing, forming part thereof.

In the drawing,

I claim:

The ornamental design for a dress, substantially as shown.
